UNITED STATES PATENT OFFICE

94,994

DESIGN FOR A DRESS OR THE LIKE

Alan F. Sandy, Minneapolis, Minn.

Application January 11, 1935, Serial No. 54,807

Term of patent 3½ years

To all whom it may concern:—

Be it known that I, Alan F. Sandy, a citizen of the United States, residing at Minneapolis, Hennepin County, Minnesota, have invented a new, original, and ornamental Design for a Dress or the like, of which the following is a specification, reference being had to the accompanying drawing, forming a part thereof, in which

Fig. 1 is a front view of the dress, showing my new design.

Fig. 2 is a front view of the neck and bodice portion of the dress, the bodice portion being shown open.

Fig. 3 is a rear view of the dress shown in Fig. 1.

I claim:

The ornamental design for a dress or the like, substantially as shown and described.

In testimony whereof, I have signed this application.

ALAN F. SANDY.
